UNITED STATES PATENT OFFICE.

ERWIN B. LOEWENBACH, OF MILWAUKEE, WISCONSIN, ASSIGNOR TO SIGMUND JOSEPH PENTLER AND OTTO R. SHORT, BOTH OF WAUSAU, WISCONSIN.

STITCHED-DOWN SHOE.

Application filed December 23, 1922. Serial No. 608,642.

To all whom it may concern:

Be it known that I, ERWIN B. LOEWENBACH, a citizen of the United States, and resident of Milwaukee, in the county of Milwaukee and State of Wisconsin, have invented certain new and useful Improvements in Stitched-Down Shoes, and I do hereby declare that the following is a full, clear, and exact description thereof.

10 This invention relates to shoes and is particularly directed to shoes of the type known as stitched down shoes.

In stitched down shoes, as heretofore constructed, two difficulties have been experienced. One difficulty has been due to the fact that the welt frequently is slightly spaced from the lower portion of the upper, or if not initially so spaced soon becomes spaced after the shoe has been in service a short time. This results in a generally unsightly appearance and allows the shoe to become stretched or warped out of shape. The other difficulty is due to the fact that the marginal edges of the inner sole frequently turn or curl upwardly, thereby producing considerable discomfort.

This invention is designed to overcome the above noted, and similar defects, and has, therefore, for its objects the provision 30 of a stitched down shoe in which the welt will be maintained in close contact with the upper, in which a shoe of lasting shape is provided, in which curling of the margins of the inner sole is prevented, and in which great flexibility is secured.

Further objects are to provide a shoe in which a support for the arch is secured, in which the required springiness, particularly upon the inner side of the sole, is secured, and in which provision is made in the finished shoe for fitting anyone of a variety of deformed or unusual types of feet.

Embodiments of the invention are shown in the accompanying drawings, in which:—

45 Figure 1 is a transverse sectional view through a shoe.

Figure 2 is a view from the under side before the outer sole has been placed in position.

50 Figure 3 is a section on the line 3—3 of Figure 2.

Figure 4 is a view of a modified form showing the upper side of the inner sole.—

such view corresponding to a section on the line 4—4 of Figure 5.

55 Figure 5 is a vertical sectional view through a shoe corresponding to the construction shown in Figure 4, and showing the foot in position with certain of the bones of the foot indicated by shade lines.

60 Referring to the drawings, and more particularly to the Figures 1 to 3 inclusive, it will be seen that the shoe comprises an inner sole 1, which is provided with a channel or bevelled marginal recess 2. The downwardly flaring edge of this recess may intersect the bottom edge of the inner sole, as shown in Figure 1. The top edge, however, of the recess intersects the vertical margin of the inner sole 1 and does not extend to the top edge of the inner sole, thereby leaving a thickened, or reinforced, edge 3 at the top of the inner sole. Upper 4 is stitched to the inner sole 1 by means of stitching indicated at 5, which passes thru such upper and diagonally through the lower portion of the inner sole.

65 This stitching is spaced a slight distance from the outer edge of the upper so as to leave a flap 6 extending outwardly therefrom. The partially finished shoe is then placed upon the outer sole 7 and a welting strip or welt 8, having either a bevelled inner edge or a substantially rounded inner edge as indicated at 9, is positioned above the flap 6 and forced inwardly towards the inner sole 1 so as to wedge or bind a portion of the upper 4 within the channel 2, as may be seen from

70 Figure 1. As the inner edge of the welt is rounded, it is to be noted that the binding occurs at substantially two points of lines around the periphery of the inner sole. While the welt is thus held in wedged position, a line of stitching 10 is passed thru the welt, thru the flap 6, and thru the outer sole 7, thereby locking the welt in its binding or wedging position.

75 From the construction thus far described, it is apparent that there will be no gaps between the welt 8 and the upper 4, such as frequently occur in stitched down shoes. It is also to be noted that the upper 4 will not stretch or pull out of position, as it is firmly wedged and locked in its correct position by means of the channeled recess and the wedge shaped welt 8. The shoe, therefore, at all

times will maintain a neat and attractive appearance and will not exhibit the defects such as found in ordinary stitched down shoes.

5 A further feature to be noted in connection with this construction is that the edges of the inner sole are thickened or reinforced, as indicated at 3, so that they will not curl, or turn upwardly to the discomfort of the 10 user. In other words, this portion 3 is left relatively intact and of substantial formation, so as to avoid this difficulty.

If desired, an arch support or shank 11, see Figures 2 and 3, may be provided and 15 may consist of a sheet of metal if desired. This shank or arch support is positioned between the inner and the outer sole, and is provided with a rearwardly extending portion adapted to fit beneath the heel. This 20 rearwardly extending portion is provided with arcuate slot 12 and with one or more apertures 13 to accommodate the nails from the heel 14, (see Figure 5). This arch support extends forwardly beneath the arch 25 of the foot and terminates along a slanting line 15, just short of the forward edge of the metatarsal bone 16, (see Figures 2 and 5). It will be seen, therefore, that this arch support or shank is rigidly braced from the 30 heel of the shoe in addition to the bracing it receives from the inner and outer soles, and that it acts somewhat in the nature of a cantilever. This forwardly extending portion may be provided with apertures 17 35 to receive suitable fastening means, if desired. In order to provide the requisite springiness along the outer side of the shoe V-shaped notches 18 are cut out in the arch support 11 so as to form in effect, a plurality of spring tongues 19 extending towards the inner side of the shoe from the body of the arch support 11, as may be seen from Figures 2 and 3.

In fitting deformed, misshapen or defective feet, it has heretofore been customary to build a shoe up and make it especially for the particular foot to be fitted. This is an extremely expensive process and is needlessly slow and complicated. In order to avoid 45 this, the shoe, forming the subject matter of this invention, may be provided with an extra sheet of material 20, upon the upper side of the inner sole 1, and such sheet of material may be secured in position by 50 means of the divergent curved V-shaped lines of stitching 21 and 22 and the transverse line of stitching 23. This construction provides a forward pocket 24, an inner side pocket 25, an outer side pocket 26, and 55 a rear pocket 27, within any of which pads, or spring fillers may be positioned. If it is found that the arch needs supporting, a pad, or filler, may be placed in the pocket 25. This support will be at the correct place to 60 give a firm, adequate and comfortable sup-

port to a weakened arch. In the form shown in Figures 4 and 5, a filler or spring held pad, 28 has been positioned in the rear pocket 27, so as to elevate the heel slightly in order to compensate for defects in the 70 foot.

It is frequently the case that callouses are formed upon the under side or sole of the foot, immediately below the forward edge of the metatarsal bone 16, or in other words, 75 upon the ball of the foot, due to the excessive weight that is frequently placed upon this portion of the foot. This defect may be corrected by inserting a suitable filler, or pad, 29 in the forward pocket 24, as shown 80 in Figures 4 and 5. This pad, as will be seen particularly from Figure 5, provides an extra bearing for the lower portion of the foot and consequently relieves the ball of the foot of the excessive weight that it previously carried.

Attention is called to the fact that the shape of the groove in the inner sole may be varied to suit the varying needs in different types of shoes, provided, that the interlocking feature of the welt and inner sole be retained. For instance, a man's heavy shoe with a heavy inner sole will have ample room for the groove. In the case of a light inner sole, it may be found necessary to provide an overlapping lip on the inner sole and an underlapping lip on the welt, thereby retaining the groove effect and securing the interlocking. 95

It will be seen that a stitched down shoe 100 has been provided in which the welt is securely held in wedging position against the upper, and in which the upper is prevented from pulling or stretching out of position.

It will further be seen that this interlocking of the inner sole and welt prevents the welt from curling upwardly at its inner edge. For example, when the welt gets wet and subsequently dries, it frequently happens that with the old type of stitched down shoe the inner edge of the welt curls upwardly, thereby materially detracting from the appearance and serviceability of the shoe. This defect is wholly overcome by this invention, and the welt will, under all 110 conditions, retain its flat position.

It will further be seen that a foot supporting shoe has been provided in which a comfortable and accurate support for the arch is secured, and in which provision has been made for fitting a great variety of defective feet. 115

I claim:

A stitched down shoe comprising an inner sole having a channeled marginal edge and upper and lower lips, an upper, securing means attaching said upper to the lower of said lips, said upper having a flap extending outwardly from said securing means, an outer sole positioned below said inner sole 125

and extending outwardly beyond said inner sole, a welt strip having a beveled inner edge wedged against said upper and forcing said upper into binding contact with the channel in said inner sole, said welt strip being free of attachment to said inner sole and being positioned flatly above the flap of said upper, and a line of stitching passing

through said welt strip, said flap and said outer sole. 10

In testimony that I claim the foregoing I have hereunto set my hand at Milwaukee, in the county of Milwaukee and State of Wisconsin.

ERWIN B. LOEWENBACH.
